UNITED STATES PATENT OFFICE.

ENOCH WHALLEY, OF WILLIMANSETT, MASSACHUSETTS.

SAFETY-CRANK FOR EXPLOSIVE-ENGINES.

1,318,037.

Specification of Letters Patent.

Patented Oct. 7, 1919.

Application filed August 24, 1918. Serial No. 251,244.

To all whom it may concern:

Be it known that I, ENOCH WHALLEY, a citizen of the United States of America, and a resident of Willimansett, in the county of 5 Hampden and State of Massachusetts, have invented a new and useful Safety-Crank for Explosive-Engines, of which the following is a specification.

My invention relates to improvements in 10 manually-operated cranking or starting devices for internal-combustion engines, and consists of a fixed, ribbed member, and certain, peculiar, vibratory or oscillatory fingers carried by the crank to act in conjunction 15 with said ribbed member, the new elements being applied to the starting elements in common use, all as hereinafter set forth.

The primary object of my invention is to provide means, in the cranking device or 20 mechanism of an explosive engine, whereby the engine can be started by hand in the ordinary manner, but injury to the operator, in case what is commonly known as "back-fire" occurs, is prevented, the effective connection 25 then being automatically broken and the crank released and left free in the hand of the operator so that he can not be injured thereby.

A further object is to provide a device of 30 this kind which is not only comparatively simple and inexpensive in construction, and simple in operation as well, but one which may readily be applied to the ordinary motor-vehicle engine at nominal cost and 35 without requiring the installation of new clutch members or the making of radical changes in the existing cranking mechanism.

Other objects and advantages will appear in the course of the following description.

40 I attain the objects and secure the advantages of my invention by the means illustrated in the accompanying drawings, in which—

Figure 1 is a top plan of a preferred form 45 of my safety device, showing the same applied to the starting mechanism of the engine of a Ford automobile, the crank proper being in inactive position; Fig. 2, a side elevation of the parts shown in the preceding view; Fig. 3, a top plan of the device, the crank being in active or operative position; Fig. 4, a front-end elevation of the device without the crank which has been 50 removed, and, Fig. 5, an inside elevation of 55 said crank.

Similar reference numerals designate similar parts throughout the several views.

I will first describe briefly the old parts herein shown of the starting mechanism with which the new parts are incorporated 60 to produce the invention, and will then describe in detail said new parts and explain the operation of the device as a whole.

Journaled in bearings 1—1 and 2, the axes of which are in alinement with each other, 65 are two shafts 3 and 4. Only the forward-end portion of the shaft 3, or the portion that is directly supported in the rear bearing 1, appears. This is the engine shaft. The other is the cranking or starting shaft 70 and has its full support in the bearing 2 and the bearing 1 which is adjacent to said bearing 2. Secured on adjacent terminals of the shafts 3 and 4, between the bearings 1, are ordinary clutch members 5 and 6, respectively. The shaft 4 is axially movable 75 in its bearings, and is normally retained in the forward or outward position, with the clutch member 6 against the forward bearing 1, as shown in Figs. 1 and 2, by 80 means of a spiral-spring 7 which encircles said shaft between the bearing 2, or a member attached thereto and presently to be described, and a crank proper 8, which latter also will presently be described. 85 The front end of the shaft 3 extends into the clutch member 6 to guide and center the latter when actuated into and out of engagement with the clutch member 5, and there is sufficient clearance, in said 90 first-named clutch member, between the adjacent shaft ends therein, to permit said member 6 to be moved rearwardly into engagement with said member 5.

Obviously, if the shaft 4 be forced 95 rearwardly to cause the clutch member 6 to engage the clutch member 5, and said shaft be rotated, the shaft 3 is rotated in the same direction, and, when the engine begins to operate by its own power, said member 6 100 is automatically disengaged from said member 5.

Passing next to the new parts, it will be observed that they comprise a circular plate or disk 9 which is provided on its front face 105 with a plurality of radial projections, or ribs 10, and the crank 8 which is provided on the inner or back side with a pair of rearwardly-extending, vibratory dogs or fingers 11.

The disk 9 is fastened against the front side or face of the bearing 2, by means of two lugs or ears 12 which extend from the back side of said disk onto the lateral flanges 5 of said bearing, to which flanges said ears are secured by screws 13—13, and the shaft 4 passes through the axial center of said disk. The ribs 10 are not ratchet-teeth, but on the contrary more nearly resemble spur 10 teeth, although as a matter of fact said ribs are not teeth in the true sense of the term, nor do they function as such, as will hereinafter be clearly seen. The ribs 7 in cross section are substantially V-shaped with convex sides.

The crank 8 has a hub 14 which is keyed or otherwise secured to the shaft 4 at the front end, and said crank also has a handle 15 at one end, about which there is, of course, nothing new, but additionally said crank extends beyond said hub in both directions, instead of in only one direction, and is provided above and below on each side of said hub, according to the position 25 of the crank, with cross-bars 16—16. And to this extent the crank 8 is different from the ordinary crank. The cross-bars 16 project laterally from the body of the crank beyond both longitudinal edges thereof.

30 The spiral spring 7 bears between adjacent sides or faces of the disk 9 and the crank 8 on its hub 14, and so tends to force said crank outwardly or forwardly and with it the shaft 4 and the clutch member 6.

35 Each finger 11 has a hub 17 which is received between a pair of lugs 18, on the back side of the crank 8, and pivoted to said lugs by a pivot 19. The axes of the two pivots 19 are in a plane common to each 40 other and to the axis of the hub 14, and the two pairs of lugs 18 are at the intersections of the cross-bars 16 with the body portion of the crank, and equidistant from said last-named axis. Thus are the fingers 45 11 located on opposite sides of the shaft 4 and equidistant therefrom, and adapted to swing on their pivots in either direction from a common plane perpendicular or at right-angles to the back side of the crank 50 8. Furthermore, the fingers 11 are located by their supporting parts and members in position to engage with their rear, free ends the disk 9 and its ribs 10. The length of each finger 11 is approximately equal to the 55 distance which separates the crank 8 from the disk 9, when the former is in its forward, inactive position, and in any event said finger is more than equal in length to the amount of travel required on the part 60 of the clutch member 6, assuming the same to be in engagement with the clutch member 5, entirely to disengage said member 6 from said member 5. The reason for this will appear presently.

65 It is desired to maintain the fingers 11

normally perpendicular to the back side of the crank 8, and to this end in the present case a pair of springs 20 is provided for each finger. The springs 20 in each pair are equal in size, length, resiliency, etc., and they have their outer or forward ends attached at 21—21 to one or the other of the cross-bars 16, at points which are equidistant from the adjacent lugs 18, and their inner or rearward ends attached at 22—22 to 75 opposite sides of one or the other of the finger 11, at points which are equidistant from the free end of the finger, said springs and finger being in a common plane.

Upon referring to Figs. 1 and 2 it will 80 be clear that the fingers 11 may extend at right-angles to the crank 8, when the latter is in inactive position and the clutch members disengaged. This is true whenever the crank 8 is so positioned that the rear ends 85 of the fingers 11 can enter between the contiguous ribs 10 without being turned aside by said ribs or any of them. Usually the crank 8 is left, when in inactive position, with the handle 15 at the bottom, and, when 90 said crank is thus left, the present arrangement of parts is such that the fingers 11 are between the ribs 10 in two pairs and positioned by the springs 20 at right-angles to the crank.

95 Each finger 11 can swing in either direction, against the resiliency of the spring 20 on either side, consequently the crank 8 can be rotated in either direction without interference on the part of the ribs 10.

100 The complete operation of the cranking or starting mechanism is described as follows:

The handle 15, while in the position above noted, is grasped and the crank 8 turned in 105 the direction of the hands of a clock, and at the same time said crank is forced rearwardly, against the resiliency of the spring 7, until the clutch member 6 engages the clutch member 5, all in the usual manner, 110 when the shaft 3 is rotated. As the crank 8 begins to turn the fingers 11 ride out from between the ribs 10 and so enable said crank, with the shaft 4 and the clutch member 6, to be forced rearwardly (see Fig. 3), and said 115 fingers click past said ribs as said crank continues to rotate. The crank may be completely rotated one or more times or until the engine starts; or said crank may be only partially rotated in the aforesaid direction, 120 then reversed, after permitting it to come forward under the influence of the spring 7 to disengage the clutch members and enable said fingers to change the directions of their deflection, and again turned clockwise, repeating as often as is necessary to 125 start the engine. Both methods are common, but the second is more generally employed. In the event, however, that the engine backfires and the shaft 3 is in con- 130

sequence rotated in reverse direction while the shaft 4 is coupled thereto, the free ends of the fingers 11, which ends are at all times in position to be engaged by the ribs 10, are engaged by two of said ribs, said ends slide along said ribs into contact with the face of the disk 9, and said fingers, by reason of their engagement with the ribs and disk thus brought about, are swung on their pivots 19 into right angular relationship with the crank 8 and force the latter forward, thus disconnecting the clutch members, freeing said crank from the influence and action of the engine shaft, and preventing injury to the operator who has the handle 15 in his grasp. The crank is freed and left inactive in the hand of the operator in ample time to safeguard the operator, as will be readily seen. After the backfire the cranking operation is resumed in like manner as before.

Although a single figure 11 would be sufficient to accomplish the desired result of throwing out the clutch whenever the engine shaft is forcibly reversed, I prefer to provide two of such fingers so that the strain on the parts will be equalized and the force which actuates the shaft 4 forward will be applied on both sides of said shaft in parallel planes therewith, instead of being applied on one side only, as in the case of single finger. The advantage of distributing and equalizing the force and strain is obvious. It is believed that more than two fingers would rarely be required or even desired.

The springs 20 serve to keep the fingers 11 in position ready for any emergency, regardless of the position or direction of rotation of the crank 8.

The fingers 11 are really thrust rods which, whenever their direction of travel is changed, coact with the disk 9 and its ribs to force the crank positively and irresistably forward, provided said crank be rearwardly disposed.

When the crank 8 is rotated the fingers 11 are deflected behind in the direction of rotation of said crank, and said fingers are crosswise relative to each other, but, of course, on widely separated planes.

More or less change in the shape and size and even in the construction and arrangement of the parts of this device may be made without departing from the spirit of my invention or exceeding the scope of what is claimed.

I am aware that various safety, cranking or starting devices, which include true ratchet and pawl elements, have been invented, and do not, therefore, seek to cover broadly any structure in which the throw-out mechanism depends upon a simple ratchet and pawl or mechanical equivalent thereof.

What I claim as my invention, and desire to secure by Letters Patent, is—

1. In a device of the class described, an endwise-movable shaft, a crank on said shaft, a swinging member extending from the arm of said crank, yielding means to retain said swinging member normally in extended position approximately at right-angles to the orbicular plane of said arm, said member being adapted to swing in either direction from said position, and a fixed member provided with ribs which are in the path of said swinging member.

2. In a device of the class described, an endwise-movable shaft, a crank on said shaft, a swinging member extending from the arm of said crank, yielding means arranged to retain said swinging member normally approximately at right-angles to the orbicular plane of said arm, and a fixed member provided with ribs which are in the path of said swinging member, the latter being adapted to swing in either direction from normal position.

3. The combination, in a device of the class described, with an engine shaft and clutch member thereon, and a fixed member provided on its face with a series of ribs spaced apart, of a starting shaft and a clutch member thereon, said last-named shaft having endwise movement and extending through said fixed member, a crank on said last-named shaft, a finger pivotally connected with the arm of said crank, and resilient means normally to retain said finger at approximately right-angles to the orbicular plane of said arm, said finger being adapted to swing in either direction from normal position, and being located with its free end in engaging relation to said ribs, and of a length sufficient to engage said fixed member and force said crank, with said starting shaft and said clutch member thereon, forward far enough to separate said clutch members, in the event said engine shaft be rotated in reverse direction while said clutch members are in engagement.

4. The combination, in a device of the class described, with an engine shaft and a clutch member thereon, and a fixed member provided on its face with a plurality of ribs spaced apart, of a starting shaft and a clutch member thereon, said starting shaft having endwise movement and extending through said fixed member, a crank on said starting shaft, a finger pivotally attached to the arm of said crank, and springs arranged normally to retain said finger at approximately right-angles to the orbicular plane of said arm, said finger being adapted to swing in either direction from normal position and being located with its free end in engaging relation to said ribs, and of a length sufficient to engage said fixed member and force said crank, with said starting shaft and said clutch member thereon.

shaft and said clutch member thereon, forward far enough to separate said clutch members, in the event said engine shaft be rotated in reverse direction while said clutch members are in engagement.

5. The combination, in a device of the class described, with an engine shaft and a clutch member thereon, and a fixed member provided on its face with a series of ribs spaced apart, of a starting shaft and a clutch member thereon, said starting shaft having endwise movement and extending through said fixed member, a crank on said starting shaft, the arm of said crank being provided with supporting means, a finger pivotally connected with said supporting means and adapted to swing into and in either direction out of a position at right-angles to the orbicular plane of said supporting means, and resilient means arranged normally to retain said finger approximately in said position, said finger being located with its free end in engaging relation to said ribs, and of a length sufficient to engage said fixed member and force said crank, with said starting shaft and said clutch member thereon, forward far enough to separate said clutch members, in the event said engine shaft be rotated in reverse direction while said clutch members are in engagement.

6. The combination, in a device of the class described, with an engine shaft and a clutch member thereon, and a fixed member provided on its face with a plurality of ribs spaced apart, of a starting shaft and a clutch member thereon, said starting shaft having endwise movement and extending through said fixed member, a crank on said starting shaft, a spring interposed between said fixed member and said crank normally to retain the latter, with said starting shaft and clutch member thereon, in the forward position, a finger pivotally connected with the arm of said crank, and resilient means normally to retain said finger at approximately right-angles to said crank, said finger being adapted to swing in either direction from normal position and being located with its free end in engaging relation to said ribs, and of a length sufficient to engage said fixed member and force said crank, with said starting shaft and said clutch member thereon, forward far enough to separate said clutch members, in the event said engine shaft be rotated in reverse direction while said clutch members are in engagement.

7. The combination, in a device of the class described, with an engine shaft and a clutch member thereon, and a fixed member provided on its face with a series of ribs spaced apart, of a starting shaft and a clutch member thereon, said starting shaft having endwise movement and extending through said fixed member, a crank on said starting

shaft, the arm of said crank being provided with supporting means, a finger pivotally connected with said supporting means and adapted to swing into and in either direction out of a position at right-angles to the 70 orbicular plane of said supporting means, and springs attached to said supporting means, on opposite sides of said arm and to opposite sides of said finger, and adapted normally to retain the latter approximately 75 in said position, said finger being located with its free end in engaging relation to said ribs, and of a length sufficient to engage said fixed member and force said crank, with said starting shaft and said clutch member 80 thereon, forward far enough to separate said clutch members, in the event said engine shaft be rotated in reverse direction while said clutch members are in engagement.

8. The combination, in a device of the class described, with an engine shaft and a clutch member thereon, and a fixed member provided on its face with a plurality of ribs spaced apart, of a starting shaft and a clutch member thereon, said starting shaft having endwise movement and extending through said fixed member, a crank on said starting shaft, said crank having arms which extend beyond said shaft in two directions, said arms having lateral projections on both sides of the transverse plane of its axis, and also having in its longitudinal center at the back supporting means, fingers pivotally connected with said supporting means and adapted to swing into 100 and in either direction out of a position at right-angles to said crank, and springs attached to opposite sides of said fingers and extending and being attached to said lateral projections, said fingers being located with their free terminals in engaging relation to said ribs, and of a length sufficient to engage said fixed member and force said crank, with said starting shaft and clutch member thereon, forward far enough to separate said 105 clutch members, in the event said engine shaft be rotated in reverse direction while said clutch members are in engagement.

9. The combination, in a device of the class described, of an engine shaft provided with a clutch member, an endwise-movable starting shaft provided with a clutch member, bearings for said shafts, a disk fixed to the front end of the foremost starting-shaft bearing and encircling said starting shaft, said disk having on its face a plurality of ribs spaced apart, a crank on said starting shaft, a spring between said disk and said crank to force the latter, with said starting shaft and clutch member thereon, forward, a finger pivotally connected with the arms of said crank, and yielding means normally to retain said finger approximately perpendicular to the orbicular plane of said arm, said finger being adapted to swing in 130

either direction from normal position and being located with its free end in engaging relation to said ribs, and of a length sufficient to engage said fixed member and force 5 said crank, with said starting shaft and said clutch member thereon, forward far enough to separate said clutch members, in

the event said engine shaft be rotated in reverse direction while said clutch members are in engagement.
